(57) **CLAIM**

The ornamental design for a walking support machine for cane, as shown and described.

DESCRIPTION

FIG. 1 is a front, top and right side perspective view of a walking support machine for cane showing our new design; FIG. 2 is a rear, top and right side perspective view thereof; FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a perspective view thereof showing the design in use; and,

FIG. 10 is another perspective view thereof showing the design in use.

The elements shown in dash-dotted broken lines in FIGS. 9 and 10 illustrate environment of the walking support machine for cane and form no part of the claimed design. The other evenly-spaced broken lines of the drawings show portions of the walking support machine for cane that form no part of the claimed design.

1 Claim, 10 Drawing Sheets
